FIG. 1.

FIG. 2.

FIG. 3.

FIG. 4.

FIG. 5.

FIG. 6.

FIG. 7.

FIG. 1 is a perspective view taken from the front, top and right side of a data entry terminal embodying our new design;

FIG. 2 is a front elevational view thereof, the rear being plain and unornamented;

FIG. 3 is a perspective view taken from the front, top and right side of a modified form of the data entry terminal shown in FIG. 1;

FIG. 4 is an elevational view taken from the left side of FIG. 1;

FIG. 5 is a fragmentary front elevational view of a second modified form of the data entry terminal shown in FIG. 1;

FIG. 6 is a fragmentary front elevational view of a third modified form of the data entry terminal shown in FIG. 1; and

FIG. 7 is a fragmentary front elevational view of a fourth modified form of the data entry terminal shown in FIG. 1.

The broken lines in FIGS. 1 through 3 indicate that the keyboard extends across the area occupied by such lines.

We claim:

The ornamental design for a data entry terminal, substantially as shown and described.
